VALVE MECHANISM

Paul C. Temple, Decatur, Ill., assignor to A. W. Cash Company, Decatur, Ill., a corporation of Delaware

Application April 21, 1939, Serial No. 269,143

4 Claims. (Cl. 137—68)

This invention relates to valve mechanisms, and more particularly to valve mechanisms of the type adapted to control the flow of fluid in accordance with pressure variations as well as changes in liquid level.

In certain apparatus for the manufacture of ice it has been proposed to employ a series of vessels forming heat exchangers arranged to effect a transfer of heat from water, through intervening metal walls, to a suitable refrigerant in liquid form. As soon as the water has been frozen in one vessel, refrigerant in gaseous form is introduced at a higher pressure to force the liquid refrigerant out of the vessel and into the next vessel in the series. The successive vessels are connected by conduits provided with valves, and these valves must be opened at the proper time to allow transfer of the liquid and closed promptly when the transfer has been effected. So far as I am aware, no valve mechanism suitable for this purpose has been disclosed heretofore.

It is accordingly one object of the invention to combine into one heat exchanger a simple, inexpensive and reliable valve mechanism particularly suitable for controlling the flow of liquid refrigerant therefrom to another heat exchanger.

It is a further object of the invention to combine with a heat exchanger for liquid refrigerant a valve mechanism arranged to open automatically upon a predetermined increase in pressure, and to close automatically upon a predetermined reduction in liquid level irrespective of such pressure increase.

It is a further object of the invention to combine with a heat exchanger for liquid refrigerant a valve mechanism particularly adapted to control the discharge of liquid therefrom, this mechanism being so constructed and arranged as to permit such discharge of liquid when the pressure thereof is increased sufficiently to actuate the mechanism and to prevent further discharge when the liquid has dropped to a predetermined level irrespective of the pressure increase.

With these and other objects in view, as will be apparent to those skilled in the art, the invention resides in the combination of parts set forth in the specification and covered by the claims appended hereto.

Referring to the drawing illustrating one embodiment of the invention, and in which like reference numerals indicate like parts,

Fig. 1 is a vertical longitudinal section through a valve mechanism;

Fig. 2 is an enlarged sectional view of the pilot valve shown in Fig. 1;

Fig. 3 is an enlarged section on the line 3—3 of Fig. 2; and

Fig. 4 is an elevation showing the valve mechanism connected to other apparatus.

The embodiment illustrated comprises a hollow valve body 10 divided internally by a U-shaped partition 11 into an inlet chamber 12 and an outlet chamber 14. The partition 11 is provided with two aligned ports 15 through which fluid may flow from the chamber 12 into the chamber 14 under the control of a vertically reciprocable seating-type main valve 16. This valve is biased upwardly toward its closed position by a coiled compression spring 18 located beneath the valve and supported by a cap 19 secured to the bottom of the body 10. This cap 19 is shaped to provide a guideway 20 for a vertical stem 21 which extends downwardly from the valve 16.

A bonnet 23 is secured to the top of the body 10, this bonnet being shaped to provide a vertical cylinder 24 directly above the valve 16, with the lower end of the cylinder in communication with the outlet chamber 14. A piston 25 is slidably mounted in the cylinder 24 and connected to the valve 16 by a vertical rod or stem 26. This piston provides a fluid-pressure actuated device which will, under certain conditions, open the valve 16 in opposition to the force of its biasing spring 18.

The fluid pressure effective on the piston 25 is controlled by a pilot valve which in turn is actuated in accordance with variations in the level of a liquid. For this purpose the bonnet 23 is divided internally by suitable partitions to provide an upper chamber 28, an intermediate chamber 29 and a lower chamber 30. The upper chamber 28 is connected by a pipe 32 to the outlet chamber 14 in the body 10, and the intermediate chamber 29 is connected by a passageway 33 in the bonnet 23 to the upper end of the cylinder 24. The lower chamber 30 communicates directly with the interior of a hollow casing 34 which is secured to the bonnet 23 at one side thereof. This casing 34 has a screw-threaded opening 36 in its upper portion, and its lower portion is connected to the inlet chamber 12 in the body 10 by means of a pipe 37 provided with a manually adjustable needle valve 38 which is partially open in the normal operation of the apparatus. Communication between the intermediate chamber 29 and the chambers

28 and 30 located respectively above and below

the same is controlled by a suitable three-way pilot valve mechanism.

The preferred construction for this pilot valve mechanism is shown in detail in Fig. 2 and comprises a cage 40, formed in two parts for convenience in assembly, and screw-threaded externally at 41 to facilitate its mounting within the bonnet 23. This cage is shaped to provide a central recess 42 from which ports 44 lead laterally to the intermediate chamber 29. In addition an outlet port 45 leads upwardly from the recess 42 to the upper chamber 28, and an inlet port 46 leads downwardly from the recess 42 to the lower chamber 30. A vertically reciprocable pilot valve 48 is mounted within the recess 42, this valve having a stem 49 extending upwardly therefrom into the port 45 and a stem 50 extending downwardly therefrom into the port 46. These valve stems are smaller in diameter than the ports and they are provided with radial ribs 51 which slidably engage the walls of the ports to guide the valve in its vertical travel. The lower valve stem 50 is surrounded by a small coiled compression spring 53 which engages a nut 54 on the lower end of this valve stem and serves to urge the valve 48 downwardly.

The pilot valve 48 is controlled by means responsive to the level of liquid in the casing 34, and for this purpose I prefer to utilize a hollow spherical float 55 which is mounted on one end of a horizontal lever 56, this lever being fulcrumed at its other end on a pin 57 supported by the bonnet 23. The lever 56 passes directly beneath the pilot valve, and the lower end of the pilot valve stem 50 rests against the upper surface of the lever near the fulcrum pin 57. These parts are so constructed and arranged that if the float 55 moves upwardly the lever 56 will raise the pilot valve 48 and close the upper port 45, whereas if the float moves downwardly the spring 53 will force the pilot valve downwardly until it closes the lower port 46.

The valve mechanism described above is arranged to control the discharge of liquid refrigerant from one vessel to another. As indicated in Fig. 4, the inlet chamber 12 in the valve body 10 is connected by a pipe 59 to a vessel 60, and the outlet chamber 14 is connected by a pipe 61 to a second vessel 62. The opening 36 in the top of the casing 34 is connected by a pipe 63 to the first vessel 60. The vessels 60 and 62 are two of a series of heat exchangers of known construction arranged to form ice by transferring heat from water to a refrigerant in liquid form.

The operation of the invention will now be described. During the freezing cycle in vessel 60 this vessel will be filled with a suitable liquid refrigerant, such as ammonia, to a comparatively high level, the pressure being maintained at a predetermined pressure of say 30 pounds per square inch. Because of the high liquid level the float 55 will be held in its raised position and the pilot valve 48 will likewise be raised, closing the upper port 45. The chamber 30 will be in communication with the upper end of the cylinder 24 through the port 46, recess 42, ports 44, chamber 29 and passageway 33. Thus the pressure in the vessel 60 will be effective on the top of the piston 25, but the main valve 16 will nevertheless be held closed by the force of the spring 18. When the freezing cycle in vessel 60 has been completed ammonia in gaseous form will be admitted to this vessel at a substantially higher pressure, and this pressure will be sufficient to force the piston 25 downwardly and open the

main valve 16 despite the force of the spring 18. Thus the liquid ammonia will be discharged from the vessel 60 through the pipes 59 and 61 to the vessel 62. When the liquid level in the first vessel 60 has fallen sufficiently the float 55 will descend and the pilot valve 48 will be moved downwardly by the spring 53, opening the outlet port 45 and closing the inlet port 46. The outlet chamber 14 will now be in communication with the upper end of the cylinder 24 through the pipe 32, chamber 28, port 45, recess 42, ports 44, chamber 29 and passageway 33. This will reduce the pressure above the piston 25, and the spring 18 will move the main valve 16 upwardly to its closed position. Upon discharge of the ice from the vessel 60 this vessel will again be filled with liquid ammonia at substantially 30 pounds pressure, and the float 55 will be raised once more to its original position. The needle valve 38 will remain in a partially open position to throttle the flow of the liquid through the pipe 37 as the liquid level changes, thus preventing the float 55 from moving too suddenly.

It will now be apparent that the invention provides a valve mechanism of a simple and reliable construction adapted to control the flow of a liquid refrigerant in accordance with both the pressure and the level of the liquid. When the pressure increases sufficiently the main valve will open, and when the liquid level drops sufficiently the main valve will close despite the increased pressure.

Having thus described my invention, what I claim as new and desire to secure by Letters Patent is:

1. In combination with a vessel arranged to be filled with liquid refrigerant at a predetermined pressure and having an outlet conduit, a valve to control the flow in the conduit, a float immersed in the liquid anterior to the valve and movable vertically between an upper position and a lower position in response to changes in the liquid level, means to maintain the valve in its closed position when the float is in its upper position and the refrigerant is at the said predetermined pressure, means to open the valve when the pressure of the refrigerant materially exceeds the said predetermined pressure and the float is in its upper position, and means to close the valve when the float is in its lower position irrespective of the pressure of the refrigerant.

2. In combination with a vessel arranged to be filled with liquid refrigerant at a predetermined pressure and having an outlet conduit, a valve to control the flow in the conduit, and biased toward its closed position, a float immersed in the liquid anterior to the valve and movable vertically between an upper position and a lower position in response to changes in the liquid level, a fluid-pressure actuated device connected to the valve and arranged to open the valve in opposition to its bias when the device is subjected to a fluid-pressure materially exceeding the said predetermined pressure, means subjecting the device to the pressure of the refrigerant anterior to the valve when the float is in its upper position, and means subjecting the device to the pressure of the refrigerant posterior to the valve when the float is in its lower position.

3. In combination with a vessel arranged to be filled with liquid refrigerant at a predetermined pressure and having an outlet conduit, a main valve to control the flow in the conduit, a fluid-pressure responsive device connected to the valve to move the same toward open position, a pilot

valve arranged to control the flow of refrigerant to the device, means to actuate the pilot valve and admit refrigerant to the device when the liquid level is above a predetermined height, and means biasing the main valve toward its closed position with a force sufficient to hold it closed when the refrigerant in the vessel is at the said predetermined pressure and arranged to yield and allow the fluid-pressure responsive device to open the main valve when the pressure of the refrigerant on the said device materially exceeds the said predetermined pressure.

4. In combination with a vessel arranged to be filled with liquid refrigerant at a predetermined pressure and having an outlet conduit, a main valve to control the flow in the conduit, a fluid-pressure responsive device connected to the valve

5 to move the same toward open position, a three-way pilot valve arranged to control the flow of refrigerant to and from the device, means to actuate the pilot valve and admit refrigerant to the device when the liquid level is above a predetermined height and to exhaust refrigerant from the device when the liquid level is below the predetermined height, and means biasing the main valve toward its closed position with a force sufficient to hold it closed when the refrigerant in the vessel is at the said predetermined pressure and arranged to yield and allow the fluid-pressure responsive device to open the main valve when the pressure of the refrigerant on the said device materially exceeds the said predetermined pressure.
